UNITED STATES PATENT OFFICE.

CHARLES J. WESTIN, OF ROCKAWAY, NEW JERSEY, ASSIGNOR TO WIREBOUNDS PATENTS COMPANY, A CORPORATION OF MAINE.

MACHINE FOR USE IN MAKING BOXES.

Application filed June 22, 1925. Serial No. 38,790.

This invention relates to machines for use in making boxes, crates or the like, and particularly to machines for stapling together box or crate parts and for applying binding wire thereto.

Among other objects, the invention is intended to provide certain improvements contributing to the efficiency and practicality of operation of such machines.

10 In the drawings:

Fig. 1 is a side elevation of a wirebound box blank machine embodying the invention.

Fig. 2 is a front elevation of the stapling end of the machine viewed from the line A—A in Fig. 1.

Fig. 3 is an enlarged side elevation of one of the staple-forming and driving units.

Fig. 4 is a sectional plan view taken on the line B—B of Fig. 3.

20 Fig. 5 is a sectional view taken on the line C—C of Fig. 4.

Figs. 6, 7 and 8 are similar views showing the parts in different positions taken by them during a staple-forming and driving 25 operation.

Fig. 9 is a front elevation of a staple-forming and driving unit seen from the line D—D in Fig. 6.

30 Fig. 10 is a front elevation of a portion 35 of the staple-forming and driving mechanism seen from the line E—E in Fig. 4.

Fig. 11 is a sectional view taken on the line F—F of Fig. 10.

Fig. 12 is an enlarged side elevation of the 35 staple-wire-feeding mechanism.

Fig. 13 is a sectional plan view taken on the line G—G of Fig. 12.

The machine selected for illustration consists generally of work-forwarding means 40 for relatively positioning box or crate parts and feeding them to staple-forming and driving mechanism which forms staples from staple stock wire automatically fed thereto, and drives the staples over binding wire into the box or crate parts.

The work-forwarding means consists of 45 endless conveyers 1 provided with work-positioning or spacer blocks (not shown) adjustably secured to the conveyers 1. The conveyers 1, which travel in channel guides 2, are trained over sprocket wheels 3 fast on a shaft 4 at the delivery end of the machine and over sprocket wheels 5 on a shaft 6 at the receiving end of the machine. The conveyer chains 1 are advanced intermit-

tently by a pawl 7 and a ratchet wheel 8 operated by an eccentric 9 on a shaft 10, as best shown in Fig. 1.

The stapling mechanism is carried by cross-bars 11 and 12. Cross-bar 11 is rigidly secured to the side-frames of the machine, while cross-bar 12 is mounted in guideways 13 formed in the side-frames of the machine, and is given an up and down movement by eccentrics 14 on shaft 10 through pitmen 15. The arrangement is such that the staple-driving is done between feed steps of the work and while the work is stationary.

Any desired number of staple-forming 70 and driving units may be secured to cross-bars 11 and 12 depending upon the number of binding wires to be stapled to the box parts. These units are substantially identical and a description of one will suffice.

The illustrative staple-forming and driving unit is best shown in Figs. 3 to 13 inclusive. It is constructed and arranged to form two staples at each cycle of operation and drive the staples in direct alignment over 80 the binding wire into the box parts a certain fixed distance apart, for example, one and three-quarter inches apart, thus permitting the work to be fed three and one-half inches between 85 stapling operations. It will be apparent that the stapling unit may be constructed and arranged to drive the staples farther apart than one and three-quarter inches and thereby permit the work to be fed more than three and one-half inches between 90 stapling operations.

Each stapling unit comprises a pair of staple-forming and driving mechanisms, each adapted to cut off a length of staple stock wire, form it into a staple and drive 95 the staple downward into the work. The two staple-forming and driving mechanisms of each unit are housed in a lower casing 17 secured to cross-bar 11, and the operating parts therefor are carried by an upper casing 16 secured to cross-bar 12.

Staple stock wires 18, from which the staples are formed, are carried by reels 19, pass over rollers 20 and are fed in pairs to each 105 stapling unit; the wire-feeding mechanism being arranged to feed intermittently a sufficient length of each wire to form a staple.

The two strands of staple stock wire 18 for each stapling unit are fed by a single feed roller 21 which cooperates with two 110

2
tension rollers 22 and 23, the outer surfaces of said rollers being knurled to grip the wires between them. One strand of wire is gripped between feed roller 21 and tension roller 22 while the other strand of wire is gripped between feed roller 21 and tension roller 23. Feed roller 21 is keyed to a shaft 24 journaled in the side-frames of the machine and is rotated intermittently by a ratchet and pawl mechanism 25 through pit man 26 and an eccentric 27 on shaft 10.

Tension roller 22 is loosely mounted on an eccentric 28 fast on a shaft 29 journaled in a bushing 30 carried by the lower casing 17.

15 Eccentric 28, through the action of a spring 31, tends to press tension roller 22 toward feed roller 21; said spring 31 being secured at one end to a bracket 32 on the casing 17 and at the other end to an arm 33 bolted to a collar 34 which is fast on shaft 29.

Tension roller 23 is loosely mounted on an eccentric 35 rotatably mounted on bushing 30, and is pressed toward feed roller 21 by the eccentric 35 through the action of a 25 spring 36 secured at one end to the bracket 32 and at the other end to an arm 37 bolted to eccentric 35.

While tension rollers 22 and 23 are independently mounted on separate eccentrics 30 and are therefore free to take different positions relative to feed roller 21, they are caused to rotate in unison by a key 38 carried by tension roller 22 which key fits in a keyway 39 formed in tension roller 23.

35 To prevent slippage between feed roller 21 and tension rollers 22 and 23, a gear 40 is secured to feed roller 21, which gear meshes with a gear 41 secured to tension roller 22.

40 Among other advantages, the arrangement of the tension rollers on independent eccentrics insures the proper feed of both strands of staple stock wire regardless of variations in the thickness of said wires, as the position of each tension roller relative to the feed roller 21 is independently controlled so that each strand of wire is firmly gripped at all times between its tension roller and feed roller 21.

45 Such arrangement also permits two wires of the same or different thicknesses to be fed by one feed roller, thus reducing the size of the stapling unit and thereby making it possible to arrange the several stapling units in closer proximity to each other.

The strands of staple stock wire 18, which are fed by feed roller 21 and tension rollers 22 and 23, pass through guide tubes 42 and over loop bars 43 fast on arms 44 pivoted at 50 45 to the front plate of lower casing 17. When the wires have been fed over the loop bars 43, staple-formers 46 descend cutting the wires and bending them over their respective loop bars to form the staples; formers 46 being provided with a cutting

edge to cooperate with a cutting edge on the guide tubes 42 to sever the wire therebetween. After the staple-formers 46 have formed staples over loop bars 43, the loop bars are forced out of line and staple-drivers 47, carried by driver plates 49, descend driving the staples from the formers 46 into the work.

The staple-formers 46 are slidably mounted in the lower casing 17 and are forced 75 downward by latches 48 pivoted to driver plate holders 59 which are suspended from upper casing 16. When formers 46 have completed the formation of the staples, latches 48 are forced out of contact with the 80 formers 46 by cam surfaces 50 formed on the front plate of lower casing 17. When latches 48 are forced out of contact with formers 46, the formers are yieldingly pressed downward against the work by 85 spring-pressed rods 51 which are secured to the upper ends of the formers 46 and are slidable in openings formed in the upper casing 16.

After latches 48 have been released from 90 contact with formers 46, driver plates 49 continue their downward movement. Cam plates 52 secured to driver plates 49 engage cam surfaces 53 on loop bar arms 44 and swing the loop bars 43 out of line. Drivers 95 47 secured to driver plates 49 then drive the staples out of the formers 46 into the work. Upon the upstroke of driver plates 49, cam plates 52 swing the loop bars 43 back into the formers 46, and the drivers 47, which slide in keyways formed in the formers 46, 100 engage the upper ends of the keyways and raise the formers 46 above the loop bars 43 to permit wires for the next staples to be fed into position by feed roller 21 and tension 105 rollers 22 and 23. Latches 48 are pressed back into their original positions above the formers 46 by springs 54.

The binding wire which is stapled to the 110 work is carried by reels 55, passes over rollers 56 suspended from the upper framework of the machine and thence under rollers 57 carried by lower casing 17, and is pulled along with the work by reason of its attachment thereto, the rollers 57 being so arranged 115 as to guide the binding wire beneath the formers 46 in position to be straddled by the staples when they are driven into the work.

The conveyers 1 and their channel guides 120 2 act as supports or anvils for the drive thrust of the stapling units located directly above the conveyers. When additional binding wires intermediate the two outside binding wires are stapled to the work, clincher blocks (not shown) may be secured to a 125 cross-bar 58 of the machine directly beneath each stapling unit intermediate the two outside stapling units.

The operation of the staple-forming and driving mechanism is best shown in Figs. 5 130

to 8 inclusive. In Fig. 5, the two staple stock wires 18 have just been fed over the loop bars 43. In Fig. 6, the formers 46 have descended and are about to cut off the wires 18 and bend them over the loop bars 43. In Fig. 7, the formers 46 have completed the formation of the staples and cam plates 52 have swung the loop bars 43 out of line. In Fig. 8, the drivers have descended and driven 10 the staples from the formers 46 over the binding wire into the box parts. Upon completion of the drive stroke the upper cross-bar 12 of the machine raises the parts to the position shown in Fig. 5 and the ratchet and 15 pawl mechanism 25 rotates feed roller 21 and tension rollers 22 and 23 the proper distance to feed in wire for the formation of the next staples; the springs 31 and 36 acting at all times to press the tension rollers 22 and 23 20 toward feed roller 21 to insure the feed of the proper length of wire through the guide tubes 42.

It will be noted that each staple-forming and driving unit forms two staples simultaneously and drives them simultaneously over a binding wire into the box parts; and that said two staples are driven in alignment longitudinally of the binding wire.

It will also be noted that the two staple-forming and driving mechanisms of each stapling unit are constructed and arranged to be housed in one casing, thus permitting the forming and driving simultaneously of two staples in direct alignment and in close proximity to each other, for example, as close together as one and three-quarter inches. This is particularly advantageous in the manufacture of wirebound boxes and crates in which the best results are obtained 35 by driving the staples approximately one and three-quarter inches apart. Heretofore wirebound box blank machines have been equipped with stapling units which formed and drove a single staple at each cycle of 40 operation. This restricted the feed steps of the work between stapling operations to a distance equal to the distance between adjacent staples and this limited the output of the machine. Applicant's tandem stapling 45 unit doubles the output of the machine by permitting feed steps of the work equal to twice the distance between adjacent staples.

It has been proposed to increase the feed steps of the work by employing two stapling 50 units located one behind the other in the direction of travel of the work. But such an arrangement is impracticable commercially because it requires the use of an extra set of 55 stapling units, and such units cannot be positioned close enough together to drive the staples in the close proximity required.

The expression, "close spaced relationship", as used in the claims to define the distance between the staples which are driven

into the work, is intended to cover the usual and normal spacing of staples now in general use in the wirebound box making art, namely a spacing of not to exceed three inches.

Obviously, the invention is not limited to the specific embodiment thereof shown for 70 purposes of illustration, as it may be embodied in various forms and may be used to advantage in various combinations and sub-combinations as defined in the sub-joined 75 claims.

Having described the invention, what is claimed is:

1. In a wirebound box blank machine, means for applying binding wire to box parts comprising, in combination, staple-forming and driving mechanism adapted to form a plurality of staples from a plurality of staple stock wires automatically fed thereto and to drive the same in close spaced relationship over a binding wire into 80 the work, and means to feed a plurality of staple stock wires to said mechanism comprising a single feed roller cooperating with a plurality of tension rollers.

2. In a wirebound box blank machine, means for applying binding wire to box parts comprising, in combination, staple-forming and driving mechanism adapted to form a plurality of staples from a plurality of staple stock wires automatically fed thereto and to drive the same in close spaced relationship over a binding wire into the work, and means to feed a plurality of staple stock wires to said mechanism comprising a single feed roller cooperating with 90 a plurality of tension rollers independently mounted and yieldingly pressed toward said feed roller.

3. In a wirebound box blank machine, means for applying binding wire to box 105 parts comprising, in combination, staple-forming and driving mechanism adapted to form a plurality of staples from a plurality of staple stock wires automatically fed thereto and to drive the same in close spaced 110 relationship over a binding wire into the work, and means to feed a plurality of staple stock wires to said mechanism comprising a single feed roller cooperating with a plurality of independently mounted tension rollers.

4. In a wirebound box blank machine, means for applying binding wire to box parts comprising, in combination, staple-forming and driving mechanism adapted to 120 form a plurality of staples from a plurality of staple stock wires automatically fed thereto and to drive the same in close spaced relationship over a binding wire into the work, and means to feed a plurality of staple stock wires to said mechanism comprising a feed roller, a plurality of tension rollers 125 cooperating therewith and each mounted

on a separate eccentric, and means yielding-
ly to press each eccentric toward said feed
roller.

5. In a wirebound box blank machine,
means for applying binding wire to box
parts comprising, in combination, staple-
forming and driving mechanism adapted
to form a pair of staples from a pair of
staple stock wires automatically feed there-
to and to drive said staples in close spaced
relationship over a binding wire into the
box parts, and means to feed a pair of
staple stock wires to said mechanism com-
prising a single feed roller cooperating with
a pair of tension rollers.

6. In a wirebound box blank machine,
means for applying binding wire to box
parts comprising, in combination, staple-
forming and driving mechanism adapted to
form a pair of staples from a pair of staple
stock wires automatically fed thereto and
to drive said staples in close relationship
over a binding wire into the box parts, and
means to feed a pair of staple stock wires
to said mechanism comprising a single feed
roller cooperating with a pair of tension roll-
ers; said tension rollers being independent-
ly mounted and each yieldingly pressed to-
ward said feed roller.

7. In a wirebound box blank machine,
means for applying binding wire to box
parts comprising, in combination, a plu-
rality of staple-forming and driving in-
strumentalities housed in a single casing and
constructed and arranged to form simultane-
ously a plurality of staples from a plurality
of staple stock wires automatically fed
thereto and to drive the same in alignment

and in close spaced relationship over a bind-
ing wire into the box parts. 40

8. In a wirebound box blank machine,
means for applying binding wire to box
parts comprising, in combination, a pair of
staple-forming and driving instrumentalities
housed in a single casing and constructed 45
and arranged to form simultaneously a pair
of staples from a pair of staples stock wires
automatically fed thereto and to drive the
same in alignment and in close spaced rela-
tionship over a binding wire into the box 50
parts.

9. In a wirebound box blank machine,
means for applying binding wire to box
parts comprising, in combination, staple
forming and driving mechanism adapted to 55
form simultaneously a plurality of staples
from a plurality of staple-stock wires auto-
matically fed thereto and to drive simultane-
ously said plurality of staples in close spaced
relationship over a binding wire into box 60
parts, and means to feed said plurality of
staple-stock wires to said mechanism.

10. In a wirebound box blank machine,
means for applying binding wire to box
parts comprising, in combination, staple 65
forming and driving mechanism adapted to
form simultaneously a pair of staples from
a pair of staple-stock wires automatically
fed thereto and to drive simultaneously said
pair of staples spaced substantially 1 $\frac{3}{4}$ 70
inches apart over a binding wire into box
parts, and means to feed said pair of staple-
stock wires to said mechanism.

In testimony whereof, I have signed my
name to this specification.

CHARLES J. WESTIN.
